UNITED STATES PATENT OFFICE

144,401

DESIGN FOR A HELICOPTER

Paul M. Lewis, Detroit, Mich.

Application March 26, 1945, Serial No. 118,714

Term of patent 14 years

(Cl. D71—1)

To all whom it may concern:

Be it known that I, Paul M. Lewis, a citizen of the United States, residing at Detroit, in the county of Wayne and State of Michigan, have invented a new, original, and ornamental Design for a Helicopter, of which the following is a specification, reference being had to the accompanying drawing, forming part thereof.

Fig. 1 is a side elevational view of a helicopter showing my new design;

Fig. 2 is a front elevational view;
Fig. 3 is a top plan view thereof; and
Fig. 4 is a fragmentary bottom perspective view.

I claim:

The ornamental design for a helicopter, as shown.

PAUL M. LEWIS.
